UNITED STATES PATENT OFFICE.

ADDISON J. SOUDERS, OF CORNWALL, ONTARIO, CANADA.

WINDOW-SHADE ROLLER.

1,184,586.

Specification of Letters Patent.

Patented May 23, 1916.

Application filed October 6, 1915. Serial No. 54,417.

To all whom it may concern:

Be it known that I, ADDISON J. SOUDERS, a citizen of the United States, residing at Cornwall, Stormont county, in the Province 5 of Ontario and Dominion of Canada, have invented a new and useful Window-Shade Roller, of which the following is a specification.

The device forming the subject matter of 10 this application is a window-shade roller, and the invention aims primarily to improve the construction of the pawls and to improve the construction of the mounting of the pawls.

15 It is within the province of the disclosure to improve generally and to enhance the utility of devices of that type to which the present invention appertains.

With the above and other objects in view 20 which will appear as the description proceeds, the invention resides in the combination and arrangement of parts and in the details of construction hereinafter described and claimed, it being understood that 25 changes in the precise embodiment of the invention herein disclosed can be made within the scope of what is claimed, without departing from the spirit of the invention.

In the accompanying drawing:—Figure 1 30 shows the invention in side elevation, parts being broken away and sectioned; Fig. 2 is a composite perspective showing the pawls and attendant parts separated; Fig. 3 is a section on the line 3—3 of Fig. 1; Fig. 4 is 35 a top plan showing one end of the roller.

In the accompanying drawings there is shown one end of a roller 1 having a recess 2 defining a shell 3 provided with opposed notches 4 receiving against rotation independently of the roller 1, a box-like bearing 5 embodying a base 6, slides 7 and a front composed of flanges 8 parallel to the base 6 and spaced apart to define an opening 9. The base 6 of the bearing 5 is 40 equipped with inwardly projecting ears 11 having openings 14, the ears being received in slots 10 formed longitudinally of the shell 3 in the interior thereof and at the end of the shell. The bearing 5 is held onto the end of 45 the roller 1 by means of a cap 23 secured to and surrounding the roller 1, the cap having a flange 24 which overlaps the outer 50 face of the bearing. Located in the recess 2 is a shaft 12 surrounded at its outer end 55 by a reinforcing ferrule 15. The invention comprises a spindle which, to all intents and

purposes is a part of the shaft 12, the spindle including a tapered shank 16 inserted into the end of the shaft 12, the spindle being denoted generally by the numeral 17. 60 In the shank 16 of the spindle 17 there is an opening 25 adapted to receive a securing element 26 mounted in the shaft 12. The spindle 17 terminates in a flattened end 18 carrying disks 19 and 20, the disk 19 65 being rotatable in an opening 21 formed in the base 6 of the bearing 5 and the disk 20 being rotatable in an opening formed by two opposed notches 22 fashioned in the edges of the flanges 8 which form the front 70 of the bearing 5.

Surrounding the shaft 12 is a spiral spring 27, one end 28 of which is secured to the shaft, the other end 29 of the spring 27 being threaded through the openings 14 in 75 the ears 11 of the bearing 5 and being secured to one of the ears. Mounted for right line movement in the bearing 5 toward and away from each other are opposed pawls 30 each comprising a lateral arm 32 and a finger 31 which is rounded at its inner corner as shown at 33. The pawls 30 tend to move by gravity toward the axis of the spindle 17 but, by inertia, when the spindle and the shaft are rotated rapidly, tend to move outwardly. The fingers 31 of the pawls engage the flattened spindle 16 between the disks 19 and 20, one pawl at a time ordinarily coacting with the spindle, as aforesaid, 80 to prevent an accidental rotation thereof. 90 The inner edges of the arms 32 of the spindle 17 coact with the edges of the spindle 17 to limit the movement of the pawls toward the axis of rotation of the spindle. When the roller 1 is rotated, as in the act of unreeling 95 the curtain therefrom, the flattened spindle 17, between the disks 19 and 20, coacts with the inner end of the finger 31 of the engaged pawl and lifts the pawl, an unreeling of the curtain thus being possible, there being no binding effect between the spindle and the pawl, by reason of the fact that the corner of the finger 31 of the pawl is rounded as shown at 33. The pawl thus will be forced outwardly, while the curtain is being 100 unreeled, but each pawl tends to move toward the axis of rotation of the roller, when the latter is brought to rest. 105

When the roller 1 is rotated rapidly, the pawls tend to fly outwardly, toward the perimeter of the roller, as is common with all pawls in devices of this type. 110

Having thus described the invention, what is claimed is:—

In a device of the class described, a roller; a bearing secured to the roller and comprising a base, sides and flanges projecting toward each other from the sides, the inner edges of the flanges being spaced apart, the base having a circular opening, and the inner edges of the flanges having semi-circular notches defining a second opening in the bearing; a shaft in the roller and including a flattened spindle, the opposite faces of which are parallel, said spindle including circular disks journaled respectively in the openings in the bearing; a spring one end of which is fixed with respect to the shaft, the other end of which is fixed with respect to the roller; and a pair of opposed pawls mounted for right line sliding movement in the bearing between the disks, the pawls

including lateral arms engaging the edges of the flattened spindle to limit the movement of the pawls toward the axis of the spindle, the pawls including approaching fingers coacting respectively with the flat parallel faces of the spindle to limit the rotation of the spindle, the inner corners of the approaching fingers being rounded; the sides of the bearing being flexible to permit relative adjustment of the flanges, and the inner edges of the flanges being spaced apart to give access to the pawls and to permit a flexure on the sides.

In testimony that I claim the foregoing as my own, I have hereto affixed my signature in the presence of two witnesses.

ADDISON J. SOUDERS.
